US0D1009986S

(12) United States Design Patent (10) Patent No.: US D1,009,986 S
(45) Date of Patent: * Jan. 2, 2024

(54) TYPE FONT(71) Applicant: Apple Inc., Cupertino, CA (US)(72) Inventors: Alan C. Dye, San Francisco, CA (US);
Aurelio Guzmán, San Jose, CA (US);
Christopher Wilson, San Francisco, CA (US)(73) Assignee: Apple Inc., Cupertino, CA (US)() Term: 15 Years(21) Appl. No.: 29/870,803(22) Filed: Feb. 6, 2023*Related U.S. Application Data

(63) Continuation of application No. 29/747,616, filed on Aug. 24, 2020, now Pat. No. Des. 977,562, which is a continuation of application No. 29/724,408, filed on Feb. 14, 2020, now Pat. No. Des. 894,266, which is a continuation of application No. 29/684,906, filed on Mar. 25, 2019, now Pat. No. Des. 875,825, which is a continuation of application No. 29/617,581, filed on Sep. 14, 2017, now Pat. No. Des. 844,049.
